Atty.

UNITED STATES PATENT OFFICE.

ELLSWORTH A. LOOMIS, OF CHICAGO, ILLINOIS.

EXTENSION-TABLE.

SPECIFICATION forming part of Letters Patent No. 555,727, dated March 3, 1896.

Application filed July 5, 1895. Serial No. 555,080. (No model.)

To all whom it may concern:

Be it known that I, ELLSWORTH A. LOOMIS, of Chicago, in the State of Illinois, have invented certain new and useful Improvements 5 in Extension-Tables, of which the following is a specification.

My invention relates to knockdown extension-tables, and one of the objects of my improvements is to provide a knockdown extension-frame.

Another of the objects is to provide vertically-adjustable rollers for a flexible top arranged to be rolled up at the ends of the frame.

I attain these objects by the means illustrated in the accompanying drawings, in which—

Figure 1 is a longitudinal vertical section of an extension-table containing my improvements, the legs being shown in fragment and the table being contracted. Fig. 2 is a similar view to that shown in Fig. 1, the table being extended. Fig. 3 is a fragment of a bottom plan view, the legs being shown in section. Fig. 4 is a detail showing a fragment of a transverse vertical section through one of the sliding rails at the side of the extension-frame. Fig. 5 is a detail showing a transverse vertical section of a fragment of 20 the table on the line of the center legs. Fig. 6 is a detail showing a top view of one of the corner-legs together with its means of attachment to the frame and some ornamental brackets. Fig. 7 is a detail showing an enlarged longitudinal vertical section of a fragment of the flexible table-top. Fig. 8 is a detail showing a top view, partly in section, of an adjustable bracket and its means of attachment to the frame.

In the drawings, A designates the flexible top, which is made of a series of slats secured to a canvas or other flexible piece of material of the proper dimensions to cover the width and greatest extension of the table.

A' designates rollers or shafts journaled in suitable bearings in adjustable brackets A², one at each end of the extensible frame.

a designates a pin which fastens the flexible top to the frame or bed-piece on which 50 the top rolls, and a' designates a crank-handle on the end of each of the shafts.

B designates the corner-legs, having a square

recess b cut out of the upper corner and provided with ornamental pieces b'.

C designates the center leg, which is attached to the end of a lower cross-bar, C'.

C² designates an upper cross-bar attached to the extension-slides E.

F designates end pieces of the extension-frame, and F' designates iron clamps through which the adjustable brackets A² are adapted to slide vertically. The end pieces of the frame are provided with suitable handles f for extending the table.

G designates the side pieces of the extension-frame, and G' sockets into which the slides E work.

D designates the center slide. d is a bolt connecting the extension-slides E to the center slide, D, said bolt working in a groove e in the extension-slide.

The extension-slides E and center slide, D, work upon rests or supports e'. Iron clamps f are fastened in the corners of the framework and form L-shaped sockets adapted to receive the L-shaped portion of the upper end of the legs B extending around the recess b. An iron strap g crosses the inner side of the socket G' at the outer end, and a similar iron strap g' crosses the inner side of the socket G' at the inner end, and a thumb-screw g² holds the slides E in the sockets, the bottom of which is shown at g³, Fig. 4. The legs B are secured in the iron clamps f' by means of a thumb-screw f², and the brackets A² are dovetailed in the clamps F', so as to slide vertically and be set and fixed in different positions therein by a thumb-screw f³. (Shown in Fig. 8.) By removing or loosening the thumb-screws f³ the brackets A², together with the shafts carrying the flexible top, may be lifted off the sliding frame, the pin a being thereby lifted out of the hole which it enters in the cross-piece C². The corner legs also may be detached by removing the set-screw or pin f², and the cross-bar C', which carries the center legs, may be detached by removing the set-screw d', and when so separated the several parts may be conveniently packed together for storage or shipment.

Having thus described my invention, what I claim, and desire to secure by Letters Patent, is—

1. In a frame for extension-tables the combination of side pieces G connected by end pieces, of sockets G' having straps g g' arranged as described, the extension-slides E 5 provided with a groove, the center slides D having a bolt adapted to the groove of the extension-slide, thumb-screws for holding the slides in the sockets, a cross-piece C' connected with the center slides and held by a thumb-screw for supporting the center legs, and L-shaped sockets f' fastened in the corners of the frame for attaching the legs B by means of thumb-screws as specified.
2. In an extension-table the combination

with an extensible frame of a pair of dovetail clamps F' connected with each end of the frame, a pair of brackets A² adapted to slide vertically in the dovetail clamps having a thumb-screw for setting the brackets in different positions in the clamps, a roller journaled in the bracket at each end of the frame and a flexible table-top having its ends connected with said rollers as specified. 15
